(57) **CLAIM**

We claim the ornamental design for a drip coffee machine, as shown and described.

DESCRIPTION

FIG. 1 is a front perspective view of a drip coffee machine showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines are for the purpose of showing environmental structure and form no part of the claimed design.

1 Claim, 8 Drawing Sheets
